UNITED STATES PATENT OFFICE.

LOUIS D. GREGG, OF HACKENSACK, NEW JERSEY.

CANE-SHIFTING APPARATUS.

1,382,292.

Specification of Letters Patent.

Patented Mar. 2, 1920.

Application filed February 4, 1919. Serial No. 274,915.

To all whom it may concern:

Be it known that I, LOUIS D. GREGG, of Hackensack, New Jersey, (whose post-office address is care The Gregg Co., Ltd., Hackensack, New Jersey,) have invented a new and useful Improvement in Cane-Shifting Apparatus, which invention is fully set forth in the following specification.

This invention is intended primarily for unloading, at a cane-mill, the lengths of sugar-cane brought in upon a car coming from the plantation, and simultaneously feeding the same onto an endless cane-carrier which leads to the cane-crushers. But it is obvious the invention is not limited to that particular manner of use, nor to that service, inasmuch as the apparatus can be used for unloading or shifting other articles.

In harvesting sugar-cane, it is cut into lengths of (say) from three to six feet, and piled up on flat-bottomed cars which then bring it to the mill. These lengths of sugar-cane are not of uniform diameter, nor perfectly straight, but are more or less crooked, so that they cannot be arranged in the car like matches in a match box; and they are slippery and quite heavy (being filled with sap). So that, when thrown into the car, they constitute a tangled mass of heavy objects, not easy to handle. Heretofore, when these laden cars reach the mill, manual labor has been largely relied on for unloading them and feeding the canes onto the endless carrier aforesaid. This work of handling them is tiresome and exhausting, and the laborers demand high wages for the work; and it is frequently difficult, if not impossible, to obtain adequate labor. Therefore mechanical unloading-devices also

have been proposed, and to some extent have gone into use, for feeding the cane from the car onto the carrier. But such machines have not proved entirely satisfactory. The canes are fed off from the top of the load, so that a mechanical device which is arranged to handle the upper portion of the load, would have to be lowered to act upon the lower portions. Heretofore this has been accomplished by mounting the unloading-apparatus pivotally, upon a pivot located off to one side, so that the apparatus can swing diagonally downward to keep in contact with the diminishing load. Such machines are quite complicated and cumbersome; and, moreover, this diagonal down-swinging has been found objectionable, in that it tends to scatter the lengths of cane,

not feeding all the canes onto the carrier, but knocking some of them off on the opposite side of the car, whence of course they have to be collected and carried by hand. And, furthermore, when such machines are used, the canes have to be arranged lengthwise of the car, as far as feasible, although it would frequently be more convenient to pile them up more or less transversely of the car. The object of the present invention is to provide what may be termed an automatic shifting-apparatus which unloads the car completely without scattering the canes, and is simultaneously feeding them at the proper rate upon the carrier.

To that end, the invention consists broadly of a framework which is movable straight up and down (in contradiction to swinging diagonally), and presenting beneath its level a horizontally-arranged and horizontally-propelled shifting-mechanism (comprising a plurality of sprocket-systems carrying a series of teeth or hooks). In its preferred form, the invention also comprises so proportioning and arranging the parts that said horizontal shifting-mechanism extends beyond both sides of the car, so as to sweep across the full width of the car. Among the additional features, the invention further comprises preferred means for the following purposes, viz: for raising and lowering the apparatus bodily, in a straight-line perpendicular course; for maintaining the horizontal arrangement of said shifting-mechanism; for driving said shifting-mechanism; and for various adjustments of the apparatus. The several features and details of the invention will be hereinafter pointed out and claimed.

The invention will be best understood by reference to the following description and the accompanying drawings, which set forth one concrete embodiment of all the features and details of one preferred specific form, as an illustration of the broad invention which might be embodied in various other species or forms. In these drawings:

Figure 1 is an end elevation of one form of the apparatus, viewed from the left of Fig. 2, and indicating the position of the parts after the car has been unloaded, the initial or inoperative position of the apparatus being indicated by dotted lines at the top of the figure; and

Fig. 2 is a side-elevation of the same, viewed from the right of Fig. 1.

Alongside the cane-mill is a railway track,

1—1, which runs in from the plantation or other location convenient for loading. One of the cars is shown in position on this track, alongside the mill, its flat bottom being represented at 2, and its sides (not shown) having been swung down or otherwise removed. The dotted line 3 indicates vaguely the contour of a full load. At 4 (see Fig. 2) is shown the trench along which runs the usual endless carrier (not shown) that leads to the crushers. In utilizing the present invention, the lengths of cane may be loaded more or less lengthwise of the car, or indiscriminately (some lengthwise, some crosswise, and some at various angles); and they may be thrown off (sidewise) onto a carrier running parallel with the car, so as to be fed lengthwise into the crushers; yet, to simplify the present disclosure, it may be assumed that the canes (so far as may be) have been arranged transversely of the car, and are to be thrown off (lengthwise) onto a carrier running at right-angles to the car.

The new apparatus comprises a perpendicularly-reciprocal framework suspended so as to be normally free to descend by gravity; and said framework carries a depending system of horizontally-arranged and horizontally-propelled feeding-devices or cane-shifting teeth or hooks to constitute the shifting-mechanism. Suitable supports for said framework, suitable means for bodily moving it and its said shifting-mechanism straight up and down, and suitable operating-connections, etc., are supplied. As shown, these supports may comprise two or more inner uprights 5, and corresponding outer uprights 6, with suitable cross-braces and roof, constituting in effect a shed.

As shown, the perpendicularly-movable framework aforesaid comprises vertical end-frames, each shaped somewhat like an A lying on its right side, and made up of a horizontal or main member 7, and above it a diagonal member 8 secured thereto at their meeting outer ends, and also a cross-member or brace 9 whose ends rigidly connect the intermediate portions of the other two members. Two (or more) of these frames are arranged parallel to one another in vertical planes extending transversely across the railway track, and are secured to one another by suitable longitudinal connections. Any suitable means may be provided whereby said framework will be suspended so as to be normally free to descend by gravity, and yet may be moved up against its own gravity or be allowed to descend under control. Said means may comprise any provision whereby said framework may be moved straight up and down (perpendicularly); but, in the form shown, framework is suspended by ropes running over pulleys to a counterweight; and each A-frame has the free ends of its two members 7 and 8 pro-

vided with guides adapted to bear against and slidably engage the adjacent upright 5, which serve as vertical guide-ways. In the present instance, these upright guide-ways are indicated as H-beams; and each guide as 70 consisting of two reverse right-angled members 10—10 (and 11—11) adapted to receive between them, slidably, one of the flanges of the adjacent upright. As shown, this end of the members 7 and 8 is provided with a 75 series of bolt-holes, by which said guides can be adjusted lengthwise of said members, so as to shift the framework horizontally (toward or away from the uprights 5, to conform with the location of the railway 80 track).

Near the top of said framework is journaled the horizontal driving-shaft 12, extending parallel to the railway track, and receiving power as hereinafter described. On 85 said shaft is fast the driving-sprocket 13 of each sprocket-system, two pairs of parallel sprocket-systems being shown in Fig. 2; and in the same vertical plane with each wheel 13, and below it, are journaled, in horizontal 90 alignment with one another, and near the lower level of the framework, its two other sprocket-wheels 14 and 15, which may be idlers. Preferably, the distance between said lower wheels 14 and 15 is greater than the 95 width of the car. Around each group (13—14—15) passes a suitable endless sprocket-chain 16. One or the other of the two lower sprocket-wheels of each system, as outer wheel 15, is preferably mounted so as to be 100 adjusted in and out, as for taking up slack of its sprocket-chain. This may be accomplished by journaling the common shaft of these outer wheels 15 in bearings that are 105 slidable longitudinally upon the frame-member 7, in connection with a set-screw 15' which may be mounted upon the frame-member 8. As here shown, a series of transverse rake-bars 17 is carried by one pair of these sprocket-systems, and a similar series 17' by 110 the other pair. Each of these rake-bars in turn carries a number of outwardly-projecting teeth or hooks 18, which depend downward beneath the lower level of the overhanging framework, in position to engage 115 the lengths of cane (or other objects) upon the car and eject the same or shift them onto the carrier. The teeth which depend from the lower section of these sprocket-systems are alined in the same horizontal zone, which 120 preferably extends beyond both sides of the car-floor 2. Upon applying power to said driving-shaft 12, the plurality of chains 16 will be propelled, and the depending horizontal ejecting-mechanism will be actuated. 125

The framework is suspended by means of two ropes or cables, 19 and 19'; each secured to it in approximately the line of its center of gravity, and passing upward over a sheave or pulley 20 (20') suspended near the 130

top of the shed, and thence off to one side and over another pulley 21 (21') to a counterweight, to assist in raising the framework, and to control the gradual lowering 5 thereof by gravity.

This shifting-mechanism is propelled in any convenient manner, as by applying power to a sprocket-wheel 22, fast on said common driving-shaft 12. And power may 10 be applied to said wheel 22 in any convenient manner; but in this particular instance, the following arrangement is employed. A link 23 is journaled upon said shaft 12; and to the outer end of said link is pivoted, by 15 means of a pivot 24, an upper link 25; while the outer end of this upper link is journaled upon a power-shaft 26, which is mounted in stationary bearings, preferably near the top of the shed, and is driven from any convenient source of power. The pivot 24 (which unites the adjacent ends of the two links 23 and 25) is thus a floating-pivot; and upon it journal two floating-wheels, as 27 20 and 28, that are fast together. By means of 25 a suitable belt or sprocket-chain, power is transmitted from a wheel 29 fast on said power-shaft 26, to one of these two floating-wheels; and a similar connection transmits power from its companion floating-wheel to 30 the above-named sprocket-wheel 22 (carried upon the frame-work). It will be seen that, by means of this floating-connection, power is applied to propel the horizontal cane-shifting mechanism during all the various 35 levels of the latter.

Referring again to the means for raising and lowering the framework: As shown, said sheaves 20 and 20' are adjustable horizontally, to be brought substantially into the 40 plane of the center of gravity of the framework. The counterweight is here shown as an elongated trough 30 located between the two outer uprights 6-6', and carrying near each end an inverted sheave 31 (31'); and each cable 19 (19') after passing over the 45 pulleys 20 (20') and 21 (21'), continues thence down and around said pulley 31 (31'), and thence up again, to be secured to the shed, as at 32 (32'). The trough 30 is loaded with weights, so as not quite 50 to counterbalance the framework and its sprocket-systems; so that, by means of comparatively little additional power, the counterweight can be readily forced downward, 55 and the framework, etc., thereby raised into the inoperative position (as indicated by the dotted lines at the top of Fig. 1), ready for receiving the next car-load of canes. Then, by (gradually) withdrawing the 60 power which had forced the counterweight down, gravity (gradually) lowers the framework until its rake-bars and hooks come into operative relation with the load to be ejected.

65 As here indicated, the power which acts

to depress the counterweight and lift the apparatus may be hydraulic. In that case it may comprise a vertical cylinder 33, with its piston 34, and its two pipes 35 and 35' which respectively connect each end thereof with 70 any suitable four-way valve (not shown), whereby they can admit water into either side of the piston while discharging the water from the other side thereof. The piston-rod extends through the lower head 75 of the cylinder, and is secured to the counterweight-trough 30, as at 36; and, if desired, bulk-heads 37 and 37' can be secured within the trough, to protect the cylinder and its piston from injury by the weights 80 placed in the end-compartments of the trough. By means of the above-mentioned valve, the rate of perpendicular movement of the framework and its direction of movement (up or down) can be absolutely controlled. Preferably, two vertical racks 38 (38') are secured along the outer face of the outer uprights 6 (6'); and a horizontal shaft 39 is journaled upon the counterweight-trough 30, and provided at each end 85 with a pinion 40 (40') in mesh with said racks. This duplicate rack-and-pinion engagement maintains the trough horizontally, throughout its upward and its downward travel, and thereby assures maintenance of 90 the horizontal position of the framework and its ejecting-system throughout the various levels of the latter.

It will be understood that the lower sections of the several sprocket-chains 16, and their transverse rake-bars (when used) and the depending teeth 18 carried thereby, with suitable means for propelling the same, constitute the ever-horizontal ejecting mechanism; and that preferably it extends beyond 105 each side of the car.

One form of the invention, in all its parts, has thus been described in full detail, but only for the sake of clearness. It is obvious that the invention is not limited to the precise construction or arrangement, or to the precise details, set forth; since it may be embodied in other forms, various parts transposed or inverted, certain parts modified, and some of the parts used to the exclusion of other parts, without in any case departing from the spirit of the invention.

The invention having been thus fully set forth, what is claimed is:

1. The combination of a perpendicularly-reciprocable suspended framework normally free to descend by gravity, horizontally-arranged shifting-mechanism carried thereby and presented below the same, suspension-means comprising a counter-weight and guides co-acting with vertical guide-ways for bodily moving said framework and maintaining it in its rectilinear and perpendicular course, and means comprising two pivoted links carrying a floating shaft for 120 125 130

- propelling said shifting-mechanism horizontally whatever the position of said framework.
2. The combination of a perpendicularly-reciprocable suspended framework normally free to descend by gravity, horizontally-arranged shifting-mechanism carried thereby and presented below the same, suspension-means comprising a counterweight and guides co-acting with vertical guide-ways for bodily moving said framework and maintaining it in its rectilinear and perpendicular course, and means for propelling said shifting-mechanism horizontally whatever the position of said framework.
3. The combination of a perpendicularly-reciprocable suspended framework normally free to descend by gravity, horizontally-arranged shifting-mechanism carried thereby and presented below the same, means comprising co-acting guides and vertical guide-ways for bodily moving said framework in its rectilinear and perpendicular course while maintaining the horizontalism of said mechanism, and means comprising two pivoted links carrying a floating shaft for propelling said shifting-mechanism horizontally whatever the position of said framework.
4. The combination of a perpendicularly-reciprocable suspended framework normally free to descend by gravity, horizontally-arranged shifting-mechanism carried thereby and presented below the same, means comprising co-acting guides and vertical guide-ways for bodily moving said framework and maintaining it in its rectilinear and perpendicular course, and means for propelling said shifting-mechanism horizontally whatever the position of said framework.
5. The combination of a perpendicularly-reciprocable suspended framework normally free to descend by gravity, horizontally-arranged shifting-mechanism carried thereby and presented below the same, means for bodily moving said framework in its rectilinear and perpendicular course, and means comprising two pivoted links carrying a floating shaft for propelling said shifting-mechanism horizontally whatever the position of said framework.
6. The combination of a perpendicularly-reciprocable suspended framework normally free to descend by gravity, horizontally-arranged shifting-mechanism carried thereby and presented below the same, means for bodily moving said framework in its rectilinear and perpendicular course, and means for propelling said shifting-mechanism horizontally whatever the position of said framework.
7. In an apparatus of the character indicated, a perpendicularly-reciprocable suspended framework normally free to descend by gravity carrying horizontally-arranged shifting-mechanism, overhead sheaves, ropes carried thereby and connected at their ends to said framework and to a counterweight respectively, in combination with a horizontal shaft journaled on said counterweight and carrying a pinion at each end, and two stationary vertical racks with which said pinions respectively co-act.
8. In an apparatus of the character indicated, a perpendicularly-reciprocable framework normally free to descend by gravity, a horizontally-arranged and horizontally-propelled shifting-mechanism presented thereby beneath its lower level, a suspension-system comprising sheaves and ropes and a counterweight for supporting said framework, and a hydraulic-control for actuating said counter-weight for raising and lowering said framework and mechanism.
9. In an apparatus of the character indicated, the combination of a perpendicularly-reciprocable framework normally free to descend by gravity, horizontally-arranged shifting-mechanism comprising a sprocket-system carried by said framework and presenting depending teeth beneath its lower level, stationary driving-means for said sprocket-system, and a flexible driving-connection between said stationary means and said system.
10. In an apparatus of the character indicated, a framework suspended so as to be normally free to descend by gravity, a plurality of parallel sprocket-systems carried by said framework and presenting downwardly depending teeth arranged in substantially the same common horizontal zone, means to move said framework with its said sprocket-systems bodily straight up and down, and means to propel said teeth along the same direction regardless of said up and down bodily movement.
11. In an apparatus of the character described, the combination with a suspended and perpendicularly-reciprocable framework normally free to descend by gravity, of unloading-mechanism carried thereby and comprising a sprocket-system presenting outwardly-projecting teeth, those teeth which are presented downwardly from the lower section of said system being alined in a common ever-horizontal zone which overlaps both sides of the receptacle such as a car-body from which objects are to be unloaded.
- In testimony whereof I have signed this specification.
- LOUIS D. GREGG.
